HOUSING FOR A TOILET TISSUE HOLDER

John F. Bonistall, Zanesville, Ohio

Application May 15, 1958, Serial No. 50,908

Term of patent 14 years

(Cl. D4—3)

FIG. 1

FIG. 2

Fig. 1 is a front perspective view of a housing for a toilet tissue holder showing my new design;

Fig. 2 is a rear perspective view thereof; and

Fig. 3 is a vertical sectional view taken on the line 3—3 of Fig. 2.

I claim:

The ornamental design for a housing for a toilet tissue holder, as shown.
